UNITED STATES PATENT OFFICE.

HERBERT C. LEONARD, OF ACUSHNET, MASSACHUSETTS, ASSIGNOR TO ATLAS TACK COMPANY, OF FAIRHAVEN, MASSACHUSETTS, A CORPORATION OF NEW JERSEY.

MAGAZINE AND FEEDER FOR SHEET-METAL STRIPS.

1,094,369

Specification of Letters Patent. Patented Apr 21, 1914.

Application filed April 1, 1912. Serial No. 687,757.

To all whom it may concern:

Be it known that I, HERBERT C. LEONARD, a citizen of the United States, and resident of Acushnet, in the county of Bristol and State of Massachusetts, have invented certain new and useful Improvements in Magazines and Feeders for Sheet-Metal Strips, of which the following is a specification.

The object of the present invention is to 10 provide a magazine for sheet-metal strips, and means for automatically moving the strips one at a time from the magazine to feeding mechanism whereby the strips are fed to a machine which operates upon the 15 strips to produce articles of merchandise.

The invention as embodied in the form 20 illustrated is especially adapted to be attached to a machine for making tacks, which machine is substantially the same as that 25 illustrated and described in U. S. Letters Patent No. 551,279, issued December 10, 1895.

In some instances tack-making machines and nail-making machines of the character 30 illustrated in the aforesaid patent have been provided with magazines for blank strips and with means for feeding the blank strips one by one from the magazine to the feeding mechanism. One characteristic feature of the present invention is that a barrel is employed to guide the blank strips to the working instrumentalities, and this barrel is provided with a longitudinal slot through which the blank strips may be inserted laterally. 35 The magazine for the blank strips is disposed at one side of the barrel in such close relation to the barrel that a blank strip in moving from the magazine into the barrel does not have far to move, the length of the movement being in no way dependent upon the length of the 40 strip. So far as I am aware, blank strips have never before been inserted into a barrel in this manner but have only been inserted into the outer end of the barrel by end-wise movement of the strip. One advantage 45 of providing the barrel with a slot and of arranging the magazine at the side of the barrel, is that a blank strip may be very quickly placed in the barrel in position to be taken by the feeding mechanism. Another 50 advantage is that much less floor space is required than if the magazine were arranged beyond the outer end of the barrel.

Of the accompanying drawings which 55 illustrate one form in which the invention may be embodied: Figure 1 represents a side

elevation of a machine for making tacks, which machine is equipped with automatic mechanism for feeding blank strips thereto from a magazine. Fig. 1^a represents a top plan view of a part of the power-transmitting mechanism included in Fig. 1. Fig. 2 represents a side elevation, on a larger scale, of the mechanism at the delivery end of the feeding attachment. Fig. 3 represents a side elevation, on the same scale as Fig. 2, of mechanism at the outer end of the feeding attachment. The relation of the mechanism shown by Figs. 2 and 3 may be had by placing Fig. 2 at the right of Fig. 3. Fig. 4 represents a cross section through the feed barrel, as indicated by line 4-4 of Fig. 3. Fig. 5 represents a cross section through the feed barrel, in the plane indicated by line 5-5 in Fig. 3, showing a stripper for causing the discharge of waste stock from the feed jaws. Fig. 5^a represents a longitudinal section through the structure shown by Fig. 5. Fig. 6 represents a longitudinal section of a portion of the feed barrel with mechanism therein for gripping a blank strip to feed the same. Fig. 7 represents a top plan view of the mechanism shown by Fig. 2. Fig. 8 represents a top plan view of the mechanism shown by Fig. 3. The relation of the mechanism shown by Figs. 7 and 8 may be had by placing Fig. 7 at the right of Fig. 8. Fig. 8^a represents a cross section indicated by line a—a of Fig. 8, showing connections for operating the automatic clutch mechanism. Fig. 9 represents a vertical section in the plane indicated by line 9-9 of Fig. 2. Fig. 10 represents a vertical section somewhat similar to that shown by Fig. 9 but taken in a different transverse plane. Fig. 10^a represents an elevation of one of the pushers by which a blank strip is transferred from the magazine to the feed barrel. Fig. 11 represents an elevation, partly in section, at the left of line 11-11 of Fig. 10. Fig. 12 represents, in perspective, a small portion of the feed barrel. Fig. 13 represents a cross section through the feed barrel, as indicated by line 13-13 of Fig. 12. Fig. 14 represents a transverse elevation, partly in section, of driving mechanism included in Fig. 9. Fig. 15 represents an elevation of gripper mechanism whereby a blank strip is fed through the feed barrel. Fig. 16 represents another elevation of the gripper mechanism turned ninety degrees about its longi- 110

tudinal axis. Fig. 17 represents an elevation of the outer end of the feed barrel and means for oscillating the barrel. Fig. 18 represents an elevation of the tack-making machine to which the feeding mechanism is attached, as viewed from the side toward which the blank strips are fed. Figs. 19, 20 and 21 represent top plan views, partly in section, of the tack-forming instrumentalities in different positions. Figs. 22 and 23 represent elevations of the tack-forming instrumentalities in different positions. Fig. 24 represents a vertical section of a portion of the tack-making machine, with the feed barrel in operative relation thereto. Figs. 25 and 26 represent elevations, partly in vertical section, of the cutters which sever the blank strip.

The same reference characters indicate the same parts wherever they occur.

A tack-making machine is illustrated on the accompanying drawings not for the purpose of limiting the present invention but solely for the purpose of showing the utility 25 of the automatic feeding mechanism and its relation to a machine for acting upon a blank strip. The tack-making machine comprises two cutters *a*, *b* (see Figs. 18 and 19) which are arranged side by side and which 30 have substantially vertical movement. The function of these cutters is to sever a small piece from the delivery end of a blank strip, which small piece is afterward formed into a tack. The cutter *a* is carried by an arm *a'* (see Fig. 24), and the cutter *b* is carried by an arm *b'*. These arms are mounted respectively on studs *a*² and *b*² about which they have a short movement. The studs *a*² and *b*² are fixed in any desired manner in a bed *c* 40 which is supported by legs *d*, the bed and legs forming the main frame of the tack machine. Upright pieces *e* extend upwardly from the bed to furnish bearings *f* for a prime power shaft *g*. This shaft is formed 45 or provided with cams *a*³ and *b*³ which act respectively upon the arms *a'* and *b'* to depress the arms. The arms are held upwardly against the cams by long leaf springs such as that indicated in Fig. 1 at *b*⁴. The spring 50 thus shown acts upon the arm *b'*, and a similar spring which acts upon the arm *a'* occupies the same relative position and is controlled by the spring *b*⁴. The cutting edges of the cutters *a* and *b* are at their lower ends, 55 and they coöperate with a fixed shear or cutter which is indicated at *h* in Figs. 24 to 26. A blank strip is indicated in Fig. 24 at *X*, and it is fed step by step from left to right with relation to that figure. Its advance 60 movement is limited by a fixed stop *i*, shown in Fig. 24. The strip is fed forward when the cutters are elevated, and when they are depressed by their respective cams they sever 65 the forward end of the strip, as shown by Fig. 25. The severed piece, indicated at *X'*,

is the blank which is afterward formed into a tack. The downward movement of the cutter *b* continues after the downward movement of the cutter *a* ceases, the cutter *b* carrying the severed piece *X'* against a resilient 70 clamping member *j* whereby the severed piece is gripped and held, as shown by Fig. 25. In the position shown by this figure, the blank *X'* is supported between two coöperative jaws *k* and *k'*. The jaw *k* is fixed, and the jaw *k'* is movable toward and from it. These jaws are formed with recesses, as shown by Fig. 26, for the reception of the blank *X'*, and their function is to tightly grip the blank while a forming tool *l* is 80 moved horizontally against a projecting end of the blank to upset the same and form a head, as shown by Fig. 23. The movable jaw *k'* is carried by an arm *k*² which is mounted upon and which turns about a stud *k*³. The arm *k*² extends upwardly into engagement with a cam *k*⁴ on the main shaft *g*. The arm is held against its cam by a leaf spring *k*⁵, shown in Fig. 1.

The forming tool *l* is affixed to an arm or lever *l'* (see Fig. 18) which is mounted upon and turns about a stud *l*². The free end of the arm is connected to the lower end of a connecting rod *l*³. The upper end of the connecting rod engages a crank pin *l*⁴ which 95 is carried by the main shaft *g*. The tack-forming instrumentalities thus far described do not form any part of the present invention, and they are mentioned and their operation is explained solely for the purpose of 100 facilitating an understanding of the utility of the feeding mechanism hereinafter described.

The blank strip *X* is guided to the tack-forming means by an element 30, which, because of the form in which it is embodied, may be appropriately termed a "barrel"; but this term is used only for the sake of brevity and is not intended to restrict the invention to any specific form of guiding 10 means. The cross section of this feed barrel throughout the greater part of its length is represented by Fig. 13. The exterior of the barrel is cylindric, its interior being grooved for the reception of the blank strip and for a gripping device whereby the blank strip is carried forward, and being formed with an elongated slot in one side through which a blank strip may be pushed laterally into the barrel. The barrel is oscillated at suitable 11 intervals through 180 degrees of a circle for the purpose of presenting the blank strip to the cutters first with one side up and then with the other side up. This is because the cutting edges of the cutters are not exactly 12 transverse to the length of the blank but are at a slight angle, for the purpose of severing the blank *X'* so that it will be relatively wide at the end where the head is formed and pointed at the other end. The barrel itself 13

is not broadly new, nor is it new to oscillate it to reverse the position of the blank. The delivery end of the barrel extends loosely through a collar 31, and the opposite end rests in a fixed bearing 32. This bearing is grooved and the barrel is formed or provided with a collar or flange 33 which fits therein and prevents endwise movement of the barrel. The collar 31 is provided with 5 oppositely disposed studs 34 which are engaged by hooks of which one is indicated in Fig. 2 at 35. These hooks are formed on a piece 35' which straddles the collar and which is affixed at the free end of a leaf spring 36. The spring is anchored at 37 to a suitable fixture. Its function is to hold the delivery end of the barrel downwardly so that the blank strip X will not jump away from the fixed cutter h. A nose or guide 38 is affixed to the delivery end of the barrel and is formed with a suitable opening 38' (Fig. 7) through which the blank strip X is fed. The nose 38 rests upon the fixed cutter h and rocks thereon when the barrel is oscillated. Adjustable guide plates p are provided near the delivery end of the barrel for the purpose of alining the blank strip with the opening 38' of the nose 38. The plates p are capable of lateral adjustment to accommodate strips of various widths.

The magazine for containing the supply of blank strips X is best shown by Figs. 1, 9 and 10. The illustrated construction includes substantially vertical guides 39 at the ends of the magazine, intermediate guides 39', and longitudinal connecting rods 40. The guides on one side are capable of lateral adjustment to accommodate strips of various widths. The magazine is of skeleton construction so that the blank strips X which are contained in it are visible. The magazine is open at the top for the introduction of the blank strips. The bottom of the magazine is a bedplate 41 whose upper surface is parallel to the axis of the feed barrel and sufficiently below the said axis to support the bottom strip so that its center will be on a level with the axis of the barrel. The side-by-side relation of the magazine and feed barrel is shown by Figs. 9 and 10. The barrel has an opening 42 in one side through which a blank strip is introduced laterally. This opening is somewhat wider than the thickness of the blank strip, because it has to receive a feeding device whereby the strip is carried forward in the barrel. The groove indicated at 43 in Fig. 13 is slightly deeper than the thickness of a blank strip, for the purpose of affording sufficient clearance to enable the strip to move freely through the barrel. The width of the groove 43 is preferably sufficient to accommodate a strip of maximum width. The barrel is provided with 65 setscrews 44 which may be set at the desired

position to engage the edge of the blank which is inserted foremost to position the blank centrally with relation to the barrel. Grooves 45, disposed at right angles with relation to the groove 43 and disposed opposite with relation to each other, afford a chamber for the reception of the feeding device which is shown by Figs. 15 and 16.

The feeding device comprises a slide 46, one end of which is provided with gripping jaws 47. The jaws are pivotally connected with each other at 48, and they are provided with extensions 49 whereby they may be operated. The extensions 49 are pivotally connected at 50 to links 51 which are connected to the slide 46 by a pivot 52. Leaf springs 53 normally close the jaws, the jaws being opened by cam surfaces formed upon the interior of the barrel, as shown by Figs. 3 and 6. These cam surfaces are indicated at 54, and they are located at a position along the length of the barrel which causes the jaws to open when they are near the point where they take hold of a new blank strip X. The function of the cam surfaces is to cause the jaws to operatively engage a new blank strip. One of the jaws 47 (see Figs. 6 and 15) is formed with a shoulder 55 which abuts against the rear end of the blank strip to prevent the strip from slipping back relatively to the jaws. The links exert closing force when the slide advances.

The slide 46 which carries the jaws is provided with fins 56 and 56' which slide in the recess 42 in the barrel and support the slide when the jaws project from the delivery end of the barrel. The fin 56 is provided with a transverse notch 57 in its outer edge whereby the slide is provided with confronting faces adapted to embrace a carrier 58. (See Figs. 3 and 4.) This carrier is mounted in suitable guides 59 on a bed 60, and is reciprocated upon the bed toward and from the tack-forming means. The connection between the jaw slide 46 and the semi-annular carrier 58 enables the feed barrel and the fin 57 to oscillate as hereinbefore described and at the same time maintains operative connection whereby the jaws are moved longitudinally in the barrel. Oscillatory movement is imparted to the feed barrel at its outer end through the medium of flexible straps 61 and 62. (See Figs. 1, 3 and 17.) One end of each strap is anchored to the periphery of the barrel. The straps extend around the barrel in opposite directions, as shown by Fig. 17, and their free ends are connected respectively to rocker arms 63 and 64. These arms are affixed to a rock-shaft 65 which is mounted in bearings afforded by a bracket 66. This bracket constitutes a part of the frame which supports the magazine and feeding mechanism, the frame including a sufficient number of legs.

67 which rest upon the floor. The frame is provided with suitable means for adjusting the height of the magazine and feeding mechanism in order to insure the desired 5 relation with the tack-forming means. This adjusting means requires no detailed description, since it is within the province of every mechanic to provide some means for the purpose explained.

10 The rocker arm 63 has an arm 68 whereby the necessary movement is caused to oscillate the barrel. At the lower end of the arm 68 is a stud 69 which is adapted to be engaged on one side by one end of an operating rod 70, and on the other by a short piece 71. The members 70 and 71 are connected by a yoke 72, which yoke is adapted to rest upon the stud 69 when it is not otherwise supported. The other end of the rod 70 (see Fig. 1) is 15 pivotally connected to an arm 73. The arm 73 is affixed to a rockshaft 74 which is mounted in suitable bearings carried by the legs of the tack machine. An arm 75, likewise affixed to the rockshaft, is connected by 20 a link 76 to a crank pin 77. This crank pin is carried by a gear 78 which is mounted upon a shaft 79. The gear is driven by a pinion 80 on the prime power shaft *g*. The effect of the crank pin 77 is to reciprocate 25 the rod 70 longitudinally. The gear 78 is provided with a radial slot 81 in which the crank pin 77 is adjustable for determining the length of oscillatory movement of the feed barrel. This movement, as previously 30 stated, is 180 degrees.

As shown by Fig. 3, the rod 70 is lifted out of engagement with the stud 69, thus 35 interrupting operative connection of the means for oscillating the barrel. The rod 40 70 is held in this position when the gripping jaws are moving back in the barrel and while a fresh blank *X* is being inserted in the barrel, after which the rod is permitted to drop into operative engagement with the 45 stud 69. It remains in operative position during the forward movement of the gripping jaws in the barrel. The rod 70 is lifted from operative position by a rod 82 which is 50 bent at its lower end to form a hook. The upper end of the rod 82 is connected by a 55 pin 83 to one arm of a bell crank 84. The bell crank is mounted upon a pivot stud 85. The pin 83, as shown by Fig. 3, is engaged and supported by a latch 86, which latch is 60 affixed to a rockshaft 87, which latch is connected to the arm 86 serves to hold the latch in the position shown by Fig. 3. An arm 89 affixed to the rockshaft 87 carries a roll 90 which stands in the path of a tripping member 91. The tripping member 91 is 65 pivotally mounted upon a cross piece 92 which is affixed to the sliding carrier 58 which moves the gripping jaws back and forth in the barrel. When the carrier 58 moves toward the delivery end of the barrel,

the tripping member 91 strikes the roll 90 and retracts the latch 86 from under the pin 83, thereby permitting the operating rod 70 to drop into operative engagement with the stud 69. The bell crank 84 is pivotally connected to one end of a connecting rod 92, the other end of which, as shown by Fig. 2, is pivotally connected to an arm 93. This arm carries a roll 94 which stands in the path of a second tripping member 95 (see 70 Figs. 1, 4 and 8) which is carried by the cross piece 92 on the carrier 58. The function of the tripping member 95 is to lift the rod 70 when the jaws in the barrel are retracted from the delivery end of the barrel. The pivot pin whereby the latch 91 is mounted upon the cross piece 92, is indicated at 75 96; and the pivot pin for the tripping member 95 is indicated at 97. As shown by Figs. 80 3 and 4, the tripping member 91 is provided with an ear 98, and the tripping member 95 is provided with an ear 99, the ears being adapted to bear against the under side of the cross piece. These ears extend in opposite directions. When the tripping member 95 is moving toward the tack machine it turns about its pivot 97, rides over the roll 94, and drops into operative position after 85 passing the roll. When it is moved in the opposite direction it engages and moves the roll 94 with the effect of lifting the rod 70 out of engagement with the stud 69. During the movement away from the tack machine the tripping member 91 rides over the roll 90 without producing any result, after which 90 it drops into operative position ready to withdraw the latch 86 from the pin 83 when the jaws are again moved forward in the barrel. The free end of the latch 86 is adapted to abut against the pin 83 when the operating rod 70 is in operative position; and when the bell crank 84 is moved to lift the rod 70, the latch 86 is automatically moved under the pin 83 by the spring 88.

When the parts are in the position shown by Fig. 3, the barrel is in position to receive a fresh blank. At this time the barrel is held in the desired position by a weight 100, which weight is attached to one end of a cord 101. The cord extends over a grooved roll 102 and is connected to the arm 68. As shown by Fig. 3, an adjustable stopscrew 104 which is threaded in a boss 103 on the feed barrel is thus held against a boss 105 on the bearing 32. The stopscrew 104 is adjusted to cause the opening 42 of the feed barrel to register with the bottom strip in the magazine.

The mechanism for inserting the blanks laterally into the feed barrel comprises a 125 plurality of pushers which are operated in unison. In the present instance there are three of such pushers. They are indicated in Figs. 1, 9, 10 and 11, at 106. The construction of one of these pushers is shown 130

best by Figs. 10 and 11, and since the construction is similar in all of them a description of one will suffice. Each pusher 106 is affixed to a slide 107. The slide is movable transversely of the barrel in a groove 108 formed in the bed 41. The pusher lies under the column of blank strips in the magazine and is formed with a shoulder 109 which is adapted to engage one edge of the bottom strip to push the strip laterally. Yielding pressers 106^x are provided, (see Figs. 9 and 10) for keeping the blank strip seated firmly upon the pushers during the movement of the strip from the magazine to the barrel. The pusher is connected to the slide 107 by a screw 110 and is formed with a slot for the reception of the screw whereby it may be adjusted to position the shoulder 109 for blanks of various widths. Each slide 107 is provided with a stud 111 on its under side, the stud extending through a slot 112 in the bed 41. Each stud is connected by a link 113 to one arm of a bell crank 114. The pivot studs for the three bell cranks are indicated at 115. The three bell cranks are pivotally connected to a connecting rod 116 which has a parallel movement. An operating rod 117 connects the rod 116 with an arm 118 (see Fig. 8). The arm 118 is mounted upon a fulcrum stud 119 and is provided with two arms, indicated respectively at 120 and 121, which carry rolls 122 and 123 respectively. The rolls lie in the plane of movement of the cross piece 92 which is affixed to the carrier 58. The cross piece is formed with oppositely inclined cam faces which are indicated respectively at 124 and 125. When the carrier is moving away from the delivery end of the barrel 40 and is near the end of such movement, the cam face 125 engages the roll 123, the result of which is a forward movement of the pushers whereby the bottom blank in the magazine is placed in the feed barrel, as shown by Fig. 9. Upon subsequent forward movement of the carrier 58 to feed forward the fresh blank, the cam face 124 engages the roll 122, thereby moving the pushers in the opposite direction to retract them from the feed barrel and to restore them to the position shown by Fig. 10.

A remnant of the blank X remains in the feed jaws when they are retracted from the tack-forming means, which remnant is carried back past the point where the jaws take hold of a new strip. After the remnant has passed the aforesaid point it strikes against stops 126 in the barrel. (See Figs. 5 and 5^a.) The movement of the waste piece is thereby arrested while the jaws continue to move, and when the jaws pass beyond the end of the remnant it is free to drop into a recess 127 in the barrel, where it remains while a fresh blank X is deposited in the barrel and until the barrel is again oscil-

lated. The recess 127 is open at one side, and the remnant is discharged from the barrel when the barrel is once more oscillated. The carrier 58, whereby the feed jaws are moved forward and back in the feed barrel, is actuated by a weight when it is feeding a strip forward, and is moved in the opposite direction by suitable driving mechanism which imparts a relatively rapid return movement. The driving mechanism also acts during the first part of the forward movement of the jaws to carry them into position to grasp the rear end of the fresh blank, and to carry the fresh blank forward until its front end is approximately in position to be severed. Thereafter, the forward movement of the blank is caused by the aforesaid weight.

The mechanism for reciprocating the carrier 58 is shown by Figs. 1, 2, 3 and 4, and includes an endless chain 128. The chain is anchored in any suitable manner to the carrier 58, and it passes over sprocket wheels 129 and 130. The wheel 129 is an idle wheel and is mounted in the bracket 66 at the outer end of the feeding mechanism. The sprocket wheel 130 is splined upon a sleeve 131 (see Fig. 14), which sleeve is pinned to a shaft 132. This shaft is mounted in suitable bearings near the delivery end of the feed barrel. The sleeve 131 has clutch teeth 133 at one end and clutch teeth 134 at the opposite end. The teeth 133 are adapted to coöperate with complementary clutch teeth whereby the sprocket is driven to carry the feed jaws away from the tack machine, while the teeth 134 are adapted to coöperate with clutch teeth whereby the carrier is advanced toward the tack machine. The clutch teeth for the forward drive are formed upon the hub of a sprocket wheel 135 (see Fig. 1^a), and the clutch teeth for the reverse drive are formed upon the hub of a sprocket wheel 136. The sprocket wheels 135 and 136 are mounted directly upon the shaft 132 but are loose with relation to the shaft. The shaft is movable endwise for the purpose of placing the sleeve 131 in driving relation to the sprocket wheel 133 or in driving relation to the sprocket wheel 134, or in a neutral position midway between those sprockets. All three of the sprockets upon this shaft are prevented from moving laterally by portions of a bracket or hanger 137 in which the shaft has its bearings. The sprocket wheel 130, being splined to the sleeve 131, is driven in one direction or the other according to whether the sleeve is in driving relation to the sprocket wheel 135 or 136.

Rotation is imparted to the sprocket wheel 135 by a chain 138 which passes over a sprocket wheel 139 on a continuously driven shaft 140. Rotation is imparted to the sprocket wheel 136 by a chain 141 which passes over a sprocket wheel 142 on a con-

tinuously driven shaft 143. The shaft 140 has a gear 144 which meshes with a gear 145 on the shaft 143, thereby causing the shafts to turn in opposite directions. Rotation is imparted to the shaft 140 by a sprocket wheel 146 and chain 147. The chain passes over a driving sprocket 148 on the prime power shaft 9 of the tack machine. The chain 147 is guided by idle rolls 149.

10 The shaft 132 is provided with a flanged collar 150 whereby it is moved to place the clutch sleeve 131 in the desired position. A forked lever 151 pivoted at 152 serves as a shipper for transmitting the desired movement to the collar 150. The lever 151 is connected by a link 153 to an arm 154 which is affixed to a rockshaft 155. The rockshaft is mounted in suitable bearings 156 at one side of the bed 60 upon which the carrier 20 58 travels, and extends longitudinally of the bed. The arm 154 is near the delivery end of the barrel and is provided with a lateral extension 157 which carries a roll 158. At the opposite end of the rockshaft 155 (see 25 Fig. 8) is an arm 159 which carries a roll 160, and at a suitable point between the ends of the rockshaft there is a third arm, which is indicated at 161. (See Fig. 8^a.)

The function of the arm 159 is to rock the 30 shaft 155 so as to shift the clutch sleeve 131 from the reverse drive to the forward drive, or, in other words, from the sprocket wheel 136 to the sprocket wheel 135. This movement is effected by a cam surface 162 35 formed upon the cross piece 92 which is carried by the carrier 58. The cam surface acts first to shift the clutch sleeve from the reverse drive to neutral position between the sprocket wheels 135 and 136, but the momentum of the carrier 58 and the parts 40 which move with it is sufficient to continue the reverse movement after the power is disconnected, because the movement which is transmitted by the clutch mechanism is a 45 relatively rapid movement. Continued movement of the carrier 58, due to momentum, causes the cam 162 to shift the clutch sleeve 131 into engagement with the sprocket wheel 135 so that power is connected 50 for driving the carrier forward.

It will be remembered that oscillatory movement of the barrel ceases shortly after the feeding jaws begin to move backward, and that during the greater part of the backward movement of the jaws the barrel remains in position to receive a fresh blank. When the jaws have nearly reached the limit of their retractive movement, the waste piece of stock is stripped from them as hereinbefore explained and a fresh blank is pushed into the side of the barrel. The placing of the fresh blank occurs immediately prior to the movement of the clutch sleeve 131 which disconnects the reverse 60 drive and connects the forward drive, so

that when the power for the forward drive is connected there is in the barrel a fresh blank to be grasped by the feed jaws. There is no appreciable dwell between the time when the reverse drive is disconnected and the time when the forward drive is connected. The feed jaws, during this drive-reversing operation, are held open by the cam faces 54 on the inside of the barrel; and as the feed jaws begin to move forward they pass on opposite sides of the rear end of the fresh blank in position to grip the blank when they pass out of engagement with the cam faces. The power for carrying the jaws forward remains connected for an instant 70 after the fresh blank has been gripped until the forward end of the fresh blank is carried nearly into position to be severed by the cutters *a*, *b*, *h*. The power for effecting the forward drive is, however, disconnected at this time and thereafter the jaws are fed forward by the weight hereinbefore mentioned but not yet described.

The operation of disconnecting the power during the forward movement of the jaws 92 is effected through the medium of the intermediate arm 161 on the rockshaft 155. This arm 161, as shown by Figs. 8 and 8^a, is connected by a link 163 to an arm 164 on the opposite side of the bed 60. The arm 164 95 is pivotally mounted upon a stud 165 and has at its upper end a roll 166 which is adapted to be engaged by the cam surface 124 on the cross piece which is carried by the carrier 58. This cam surface, as hereinbefore explained, engages a roll 122 for retracting the pushers by which a fresh blank is deposited in the barrel. The cam surface, after retracting the pushers, strikes the roll 166, thereby rocking the shaft 155. This 105 movement of the rockshaft shifts the clutch sleeve 131 from the forward drive to its neutral position. The feed jaws are thereafter carried forward by a weight 167 which is suspended by a cord 168, one end of which 110 is anchored at 169 and the other end of which is attached to the under stretch of the endless chain 128 at a suitable point of the latter. The cord passes over an idle roll 171 which is supported by the bracket 66, 115 and also passes around a sheave 170 with which the weight 167 is provided. The effect of the weight is to draw the under stretch of the chain away from the tack machine, thereby causing the upper stretch 120 of the chain to move toward the tack machine. The carrier 58, being attached to the upper stretch of the chain, is therefore carried toward the delivery end of the barrel by the weight.

When the cutters *a* and *b* of the tack machine are elevated, the blank strip is fed forward by the weight until the forward end of the strip abuts against the stop *i*. Then when the cutters descend and sever the end 130

of the strip, the remaining portion of the strip is held against the cutters by the weight; and thereafter when the cutters rise above the strip, the strip jumps forward under the influence of the weight until it once more abuts against the stop *i*. During this forward step-by-step movement of the blank the barrel is being oscillated, as hereinbefore explained, so as to present the blank to the cutters first with one side up and then with the other side up.

When the feed jaws reach the limit of their forward movement, the clutch sleeve 131 is shifted into engagement with the sprocket wheel 136 by which power is connected for retracting the jaws. This movement of the clutch sleeve is occasioned by the coöperation of the fin 56 which projects from the jaw slide 46, and the roll 158 which is carried by the rocker arm 154, 157. The movement of the rockshaft 155, which is occasioned by the cam surface 124 during the forward movement of the carrier 58, places the roll 158 in the path of movement of the fin 56. Consequently, when the fin is moved forward as far as the roll 158, it strikes the roll during its oscillatory movement, thereby actuating the arm 154, 157 and shifting the clutch sleeve 131 from its neutral position into engagement with the sprocket wheel 136. The endless chain 128 is thereupon driven in the reverse direction at relatively high speed until the carrier 58 has been so far retracted as to cause the cam 162 to strike the roll 160, as hereinbefore explained.

Having thus explained the nature of my said invention and described a way of constructing and using the same, although without attempting to set forth all the forms in which it may be made or all the modes of its use within the scope of the claims, I claim:

1. The combination with instrumentalities for operating upon a blank strip; of a barrel for guiding a blank strip to potential working relation to said instrumentalities, means movable through said barrel for feeding a blank strip therein to said instrumentalities, a magazine for blank strips, and means for transferring a blank strip from said magazine into said barrel in position to be operatively engaged by said feeding means.

55 2. The combination with instrumentalities for operating upon a blank strip; of a barrel for guiding a blank strip to potential working relation to said instrumentalities, a magazine for blank strips, means for transferring a blank strip from said magazine into said barrel, and means for gripping a blank strip deposited in said barrel, said gripping means being movable in said barrel toward and from said instrumentalities for feeding the blank strip thereto.

3. The combination with instrumentalities for operating upon a blank strip; of means for guiding a blank strip to said instrumentalities, bodily movable strip-engaging means for feeding a blank strip along said guiding means, disconnectible means for feeding said strip-engaging means toward said instrumentalities, disconnectible means for retracting said strip-engaging means, and means controlled by said strip-engaging means for alternately connecting and disconnecting said feeding means and said retracting means to reciprocate said strip-engaging means.

4. The combination with instrumentalities for operating upon a blank strip; of strip-engaging means movable toward and from said instrumentalities for moving a blank strip, weighted means for moving said strip-engaging means toward said instrumentalities, disconnectible power-driven means for moving said strip-engaging means in the opposite direction, and means for connecting and disconnecting said power-driven means to effect reciprocation of said strip-engaging means.

5. The combination with instrumentalities for operating upon a blank strip; of strip-engaging means movable toward and from said instrumentalities for moving a blank strip, weighted means for moving said strip-engaging means in one direction, disconnectible power-driven means for moving said strip-engaging means in said one direction, disconnectible power-driven means for moving said strip-engaging means in the opposite direction, and controlling means for alternately connecting and disconnecting first one and then the other of said power-driven means to move said strip-engaging means in one direction and then in the opposite direction, said controlling means being adapted to leave both of said power-driven means disconnected during a period of time to permit said weighted means to move said strip-engaging means.

6. The combination with instrumentalities for operating upon a blank strip; of strip-engaging means movable toward and from said instrumentalities for moving a blank strip, disconnectible power-driven means for moving said strip-engaging means forward to place a blank strip in potential working relation to said instrumentalities, weighted means for feeding said strip-engaging means toward said instrumentalities, disconnectible power-driven means for moving said strip-engaging means in the reverse direction, and controlling means operative by the strip-engaging means at the finish of its feeding movement for connecting said reversing means, said controlling means being operative by said strip-engaging means, at the finish of its reverse movement, for disconnecting said reversing means and for con-

necting said forward-driving means, said controlling means being operative by said strip-engaging means for disconnecting said forward-driving means when a fresh blank strip is moved to potential working relation with said instrumentalities.

7. The combination with instrumentalities for operating upon a blank strip; of a barrel, gripping means movable therein toward and from said instrumentalities for feeding a blank strip thereto, said barrel having longitudinal surfaces for guiding said means and longitudinal surfaces for guiding the strip, means for reciprocating said gripping means, and means for placing a blank strip in position to be gripped and fed by said gripping means.

8. The combination with instrumentalities for operating upon a blank strip; of a barrel, means movable therein for gripping a blank strip, means for moving said gripping means toward and from said instrumentalities, said barrel having surfaces for guiding said gripping means and surfaces for opening said gripping means, and means for placing a blank strip in said barrel in position to be gripped by said gripping means.

9. The combination with instrumentalities for operating upon a blank strip, of means for gripping a blank strip, means for moving said gripping means toward said instrumentalities to feed the strip thereto, means for retracting said gripping means from said instrumentalities, and means for engaging the remnant of the strip to remove the same from said gripping means.

10. The combination with instrumentalities for operating upon a blank strip; of means for gripping a blank strip, means for moving said gripping means toward and from said instrumentalities to feed the strip and retract the remnant thereof, means for engaging said remnant to remove it from said gripping means when the latter is retracted, whereby the remnant is discharged, and means for placing another blank strip between said gripping means and said instrumentalities in position to be operatively gripped.

50 11. The combination with instrumentalities for operating upon a blank strip; of a slide movable toward and from said instrumentalities, guiding means therefor, pivotally-connected jaws disposed between said slide and said instrumentalities, said jaws being operatively engaged with said guiding means to slide therein, and pivotal connections between said slide and jaws adapted to exert closing force on said jaws when the 60 thrust of said slide is opposed by counter-thrust of the strip.

12. The combination with instrumentalities for operating upon a strip, of means for feeding a strip to said instrumentalities, and

means having surfaces for engaging and guiding said feeding means and surfaces for engaging and guiding the strip being fed.

13. The combination with instrumentalities for operating upon a blank strip; of means for guiding a blank strip to potential working relation to said instrumentalities, said means being movable for positioning the strip with relation to said instrumentalities and having a side opening for the insertion of a strip, a magazine for blank strips, means for transferring a blank strip from said magazine into said guiding means and means for gripping a blank strip deposited in said guiding means, said gripping means being movable in said guiding means toward and from said instrumentalities for feeding the blank strip thereto.

14. The combination with instrumentalities for operating upon a blank strip; of means for guiding a blank strip toward said instrumentalities, said means being capable of rotative movement about a longitudinal axis, means movable bodily through said guiding means for gripping a blank strip therein, said gripping means being capable of rotative movement with the guiding means, and means for moving said gripping means step by step in one direction through said guiding means to feed the strip to said instrumentalities.

15. The combination with instrumentalities for operating upon a blank strip; of means for engaging and supporting a blank strip, said means having a side opening for the insertion of a blank strip, means movable therein toward and from said instrumentalities for feeding a blank strip thereto, said strip-supporting means having internal longitudinal guiding surfaces for guiding said feeding means, means for operating said feeding means, a magazine for blank strips, and means for transferring a blank strip from said magazine into said strip-supporting means between said instrumentalities and said feeding means when the latter is retracted from said instrumentalities.

16. The combination with instrumentalities for operating upon a strip, of means for feeding a strip to said instrumentalities, means having surfaces for engaging and guiding said feeding means and surfaces for engaging and guiding the strip being fed, and means for placing a strip in cooperative engagement with said strip-guiding surfaces and in position to be operatively engaged by said feeding means.

17. The combination with instrumentalities for operating upon a blank strip; of strip-supporting and guiding means, means movable therein for gripping a blank strip, means for moving said gripping means toward and from said instrumentalities, said strip-supporting means having surfaces for

guiding said gripping means and surfaces for opening said gripping means, and means for placing a blank strip in said supporting and guiding means in position to be gripped by said gripping means.

18. The combination with instrumentalities for operating upon a blank strip; of an oscillatory element for guiding a blank strip to said instrumentalities, means for oscillating said element to present said strip in different positions to said instrumentalities, strip-engaging means movable in said element for feeding a strip therethrough, and operating means for moving said strip engaging means forward and back in said oscillatory element, said operating means having co-operative members one of which oscillates with said element relatively to the other, said members being adapted to pre-
serve operative connection.

19. The combination with instrumentalities for operating upon a blank strip; of an oscillatory element for guiding a blank strip to said instrumentalities, said element having a side opening, means for inserting a blank strip through said opening, means for oscillating said element to present the blank strip in different positions to said instrumentalities, strip-engaging means movable in said oscillatory element for feeding a blank strip therethrough, said feeding means having a portion projecting through said opening, and operating means engaging said projecting portion for moving said strip engaging means back and forth in the oscillatory element, said operating means and said projecting portion being adapted to maintain operative engagement when the oscillatory element oscillates.

20. The combination with instrumentalities for operating upon a blank strip; of an oscillatory element for guiding a blank strip to said instrumentalities, means for oscillating said element, said element having a side opening for lateral insertion of a blank strip, means for inserting a strip through said opening, and means for feeding the strip in said oscillatory element to said instrumentalities.

21. The combination with instrumentalities for operating upon a blank strip; of means for guiding a blank strip to said instrumentalities, said means having a side opening for lateral insertion of a blank strip, means for inserting a strip through said opening, and means for feeding the strip through said guiding means to said instrumentalities.

22. The combination with instrumentalities for operating upon a blank strip; of oscillatory means for guiding a blank strip to said instrumentalities, said means having a side opening for lateral insertion of a blank strip, a magazine for blank strips,

means for removing a blank strip from said magazine and placing it through said opening into said guiding means, and means for feeding the strip to said instrumentalities.

23. The combination with instrumentalities for operating upon a blank strip; of means for guiding a strip to said instrumentalities, said means having a side opening for lateral insertion of a blank strip, a magazine for blank strips, means for feeding a strip through said guiding means to said instrumentalities, and means operated by said feeding means for transferring a strip from said magazine through said opening and into said guiding means.

24. The combination with instrumentalities for operating upon a blank strip; of means for guiding a blank strip to said instrumentalities, said means having a side opening for lateral insertion of a blank strip, a magazine for blank strips, means movable toward and from said instrumentalities for feeding a strip through said guiding means, and means for transferring a blank strip from said magazine through said opening and into said guiding means, said feeding means having provisions for operating said transferring means to transfer a blank strip when the feeding means moves in one direction, and for returning said transferring means to initial position when the feeding means moves in the opposite direction.

25. The combination with instrumentalities for operating upon a blank strip; of means for guiding a blank strip to said instrumentalities, said means having a side opening for lateral insertion of a blank strip, a magazine for blank strips, means for feeding a blank strip to said instrumentalities, means for transferring a blank strip from said magazine through said opening and into said guiding means, disconnectible clutch mechanism for driving said feeding means, and means carried by said feeding means for actuating said transferring means and said clutch mechanism.

26. The combination with instrumentalities for operating upon a blank strip; of means for guiding a blank strip to said instrumentalities, said means being capable of oscillation about its longitudinal axis for presenting said strip in different positions, and having a side opening for lateral insertion of a blank strip, means for inserting a blank strip into said guiding means through said opening, means for feeding the strip in said guiding means, disconnectible means for oscillating said guiding means, means for disconnecting said oscillating means, and means for positioning said guiding means rotatively for the reception of a fresh strip.

27. The combination with instrumentalities for operating upon a blank strip; of means for guiding a blank strip to said in-

- strumentalities, said means being capable of oscillation about its longitudinal axis for presenting said strip in different positions, and having a side opening for lateral insertion of a blank strip, means for inserting a blank strip into said guiding means through said opening, means for feeding the strip in said guiding means, disconnectible means for oscillating the guiding means, 10 means for disconnecting said oscillating means, a stop for limiting oscillatory movement of said guiding means to determine the strip-receiving position thereof, and yielding means acting upon said guiding means 15 to turn it to strip-receiving position.
28. The combination with instrumentalities for operating upon a blank strip; of means for guiding a blank strip to said instrumentalities, said means being capable of oscillatory movement about its longitudinal axis for presenting the strip in different positions, and having a side opening for lateral insertion of a blank strip, a stop for limiting oscillatory movement of said guiding 20 means, a weight connected to said guiding means to turn it against said stop, means for inserting a blank strip into said guiding means through said opening when the guiding means is against said stop, disconnectible 25 means for oscillating said guiding means, and means for feeding the strip toward said instrumentalities.
29. The combination with instrumentalities for operating upon a blank strip; of means for guiding a strip to said instrumentalities, said means being capable of oscillatory movement about its longitudinal axis for presenting the strip in different positions, and having a side opening for lateral 30 insertion of a blank strip, disconnectible means for oscillating said guiding means, means for feeding a blank strip to said instrumentalities, said feeding means having provisions for disconnecting and connecting 35 said oscillating means, means for inserting a blank strip into the guiding means through said opening, and means for positioning said guiding means in strip-receiving position.
30. The combination with instrumentalities for operating upon a blank strip; of means for guiding a blank strip to said instrumentalities, said means being capable of oscillatory movement about its longitudinal axis for presenting the strip in different positions, and having a side opening for lateral insertion of a blank strip, means 40 for inserting a blank strip in said guiding means through said opening, means for feeding the blank strip toward said instrumentalities, disconnectible means for driving said feeding means, and disconnectible means for oscillating said guiding means, said feeding means having provisions for disconnecting and connecting 45 said driving means, and for disconnecting and connecting said oscillating means, and for actuating said blank-inserting means.
31. A machine of the character described having instrumentalities for operating upon a blank strip, and a barrel for guiding a blank strip to said instrumentalities, said barrel having an opening in its side for receiving a blank strip, said barrel being movable to one position for receiving a blank strip through said opening, and to another position for adjusting the blank strip relatively to said instrumentalities.
32. A machine of the character described having means for feeding a blank strip, oscillatory means for guiding the feeding movement of said strip and for turning the strip, said oscillatory guiding means being open at one side to enable a blank strip to move laterally from outside said guiding means into coöperative relation therewith.
33. The combination with instrumentalities for operating upon a blank strip; of means for feeding a blank strip to said instrumentalities and for retracting a remnant of such strip from said instrumentalities, and means for causing the discharge of such remnant when the latter is retracted from said instrumentalities.
34. The combination with instrumentalities for operating upon a blank strip; of means for engaging a blank strip for feeding the same, said means being movable toward and from said instrumentalities, means for giving a blank strip to said feeding means when the latter is retracted, means for moving said feeding means toward said instrumentalities to feed a blank strip and for moving said feeding means away from said instrumentalities beyond strip-receiving position to retract a remnant of strip, and means for causing the discharge of such remnant from said feeding means beyond strip-receiving position.
35. The combination with instrumentalities for operating upon a blank strip; of strip-engaging means movable toward said instrumentalities for feeding a blank strip and movable away from said instrumentalities for retracting a remnant of such strip, a stop between the limits of movement of said strip-engaging means for engaging such remnant to free it from said feeding means, and means for placing a new blank strip in the path of said feeding means and between said stop and said instrumentalities.
36. The combination with instrumentalities for operating upon a blank strip; of means for guiding a blank strip to said instrumentalities, strip-engaging means for feeding a blank strip toward said instrumentalities and for retracting a remnant of such strip, means for causing the discharge of such remnant from said strip-engaging

means, said strip-guiding means being open at one side to permit the discharge of such remnant therefrom, and means for placing a new blank strip in the path of said feeding means and between said instrumentalities and the discharging point of the remnant.

37. The combination with instrumentalities for operating upon a strip, of means for feeding a strip to said instrumentalities, and means having surfaces for engaging and guiding said feeding means and confronting surfaces for engaging opposite surfaces of the strip to guide the feeding movement of the latter.

15 38. A machine of the character described

having instrumentalities for operating upon a blank strip, and means for guiding a blank strip to said instrumentalities, said guiding means having a longitudinal opening for receiving a blank strip, said guiding 20 means being adapted to oscillate to present the sides of the strip alternately to said instrumentalities for operating thereupon.

In testimony whereof I have affixed my signature, in presence of two witnesses.

HERBERT C. LEONARD.
